HAROLD L. LEVIN, OF NUTLEY, NEW JERSEY, ASSIGNOR TO THE FLINTKOTE COMPANY, OF BOSTON, MASSACHUSETTS, A CORPORATION OF MASSACHUSETTS

WATERPROOF BOARD AND METHOD OF PREPARING SAME

Application filed September 17, 1928. Serial No. 306,477.

This invention relates to improvements in plaster board commonly comprising an inner cementitious core of stucco, plaster, or the like, having outer surface coverings of 5 absorbent paper.

More particularly my invention relates to waterproof plaster boards of the type indicated and to improved methods of manufacturing the same.

10 Numerous attempts have been made in the art to produce waterproof plaster board. These generally have concerned themselves with the incorporation of a waterproofing medium as a separate layer in the plaster 15 board structure. In some cases this layer of waterproofing material has been interposed between the opposed surfaces of the inner core and the covering plies, but this expedient has usually resulted in an insecure 20 bond between the surfacing ply or plies and the plaster core. In other cases, in order to provide a better bond between the covering sheets and the plaster core, the waterproofing layer has been applied over the exterior 25 of the surfacing ply or plies. This procedure, however, results in a smooth water-repellent surface to which it is very difficult to apply plaster, the plaster not being readily adherent to such a surface. Furthermore, in ei- 30 ther of the foregoing practices, if the waterproofing material is applied to the structure prior to the complete setting and hardening of the core material, there is a further difficulty in that the waterproofing layer inter- 35 feres with the complete setting and hardening of the core. In order to eliminate the foregoing objections, it has also been proposed to apply to the usual plaster board 40 structure having absorbent surface plies, an additional ply secured to one of the absorbent surface plies by means of an interposed film of waterproofing substance so that the structure could be waterproof and yet have 45 a surface thereof sufficiently absorbent to enable the plaster to be adherent thereto. This last type of plaster board, however, is costly to manufacture, not only because it entails the use of more material, but because 50 of the manufacturing problems that must be

met in associating the several plies with the cementitious core.

My invention has for one of its principal objects the production of waterproof plaster board in which the waterproofing medium is 55 associated in the structure in a manner which will not interfere with the drying and hardening of the core or with the proper bonding of the surface coverings to the material of the core or to the plaster subsequently applied to the surface of the board.

60 In accordance with one embodiment of my invention I may employ the usual form of absorbent sheets as the surface coverings and interpose between the opposed surfaces of 65 the sheets and the inner core, a layer of waterproofing material carried in an aqueous medium. More specifically, in accordance with my invention, I utilize a dispersion of 70 waterproofing material carried in an aqueous 75 the water being in the external phase of the dispersion and the waterproofing substance being dispersed as finely divided particles comprising the internal phase. By the use 80 of waterproofing material in the form of a dispersion, as thus briefly described, I find that the penetration of the water contained in the dispersion into the porous surfacing sheet 85 and the non-repellent relation between the dispersion and the green unset material of the core, permit the surfacing sheet or sheets to be securely bonded to the core without interfering with the proper and complete setting of the cementitious material of the core 90 and yet leaving the outer surface of the cov- 95 ering sheet or sheets in an absorbent condition for the reception and permanent retention of plaster thereon. The dispersion which I may use in carrying out my invention may be one of any of the types well known in the art. Preferably, the waterproofing material dispersed in the aqueous vehicle is of a bituminous character and is substantially non- 100 fluid at normal temperatures. I find that asphalt having a melting point of between 100 and 200° F. is suitable for the purposes of my invention. The bituminous material may be dispersed in accordance with any desired method known to the art, the dispersing agent comprising any one of a number of 105

materials known to serve this function, such as soap, sulphonated oils, clays of various types, gums, metallic oxides and powders or the like. The dispersions produced with these different types of dispersing agents vary in their stability over quite a range, those made with material such as soap being generally of less stable character than those made with materials such as clays, metallic oxides and similar powder-like mineral colloids. While the objects of my invention may be achieved with dispersions produced with any of the aforesigned dispersing materials, I find that the maximum advantages are obtained when using dispersions of the more stable variety, namely, those made with colloidal mineral powders such as clays, metallic oxides and the like, inasmuch as these latter types of dispersions exhibit the property, generally, of setting to a coalescent film only after the complete removal of the aqueous phase thereof. By virtue of this characteristic property, these dispersions permit the moisture of the core to be evaporated prior to complete coalescence of the dispersion film, for as long as any water or moisture is present in the core, the dispersion film in contact with the core will not coalesce sufficiently to seal in and prevent the complete elimination of water from the core. A dispersion of this character suitable for the purposes of my invention may comprise generally from 40 to 60% of the bituminous material as the dispersed base, 2 to 15% of the dispersing agent and the balance water. It will be appreciated, of course, that dispersions of the type set forth are generally miscible with water in substantially all proportions, and hence, if the consistency of the dispersion is too thick for applying the same in the manner to be hereinafter described, water may be added to thin the dispersion to the desired consistency.

I have shown in the drawings a conventional arrangement for carrying out the foregoing embodiment of my invention. As here illustrated, one of the surface coverings 10 is fed from a roll 11 and another similar sheet 20 is fed from a similar roll 21, the two sheets being brought together in opposed spaced relation for the reception of the cementitious material of the core therebetween, in accordance with the usual practice. At any convenient time prior to the introduction of the cementitious material between the opposed covering sheets, I apply to the upper surface of the sheet 10 a relatively thin layer of an aqueous dispersion of waterproofing material of the character described, this material being supplied by any convenient means as indicated at 12. The dispersion thus deposited on the sheet may be leveled or doctored off to provide a layer of uniform thickness, as by means of a suitable doctor blade 13. A similar layer of waterproofing mate-

rial in aqueous dispersed form may be applied to the lower surface of the sheet 20 in any convenient way. I have shown for this purpose, in Fig. 1, a supply box 22 containing the dispersion material of desired consistency, and a rotating roll 23 partially submerged in the material in the supply box and arranged to pick up a layer of the material as it rotates and apply the same in the form of a film of uniform thickness to the surface of the sheet 20. If desired, the dispersion may be similarly applied by means of a roll to the sheet 10, or suitable spraying equipment may be used in lieu of the means conventionally shown. It will be appreciated by those skilled in the art that as the water is eliminated from the aqueous dispersion, the dispersed particles coalesce to form a continuous film of the waterproofing material, the relative speed with which the coalescence of the dispersed particles is initiated, depending somewhat upon the type of dispersing agent used in producing the dispersion. The plastic material for the inner core is introduced between the opposed coated surfaces of the covering sheets while the dispersion coating material is still wet and before it has coalesced to any substantial extent. The supply of the plastic material is indicated at 30, a sluice or similar feed means 31 being shown for delivering the same from the supply means to the space between the covering sheets. The illustration in the drawing shows the plastic material as being introduced substantially immediately after the covering sheets are coated with the dispersion material but this showing is for purposes of illustration only and the introduction of the plastic material between the covering sheets may be delayed more or less, although it should be introduced prior to any substantial coalescence of the dispersion coatings.

After the plastic material has been applied, the structure is then conveyed to suitable drying means to assist in setting the plaster core as well as in effecting coalescence of the dispersion films between the core and the covering sheets. Inasmuch as the waterproofing material is carried in an aqueous medium and is thus miscible with the plastic material of the core, the coalescence of the interposed layer of waterproofing material does not in any way interfere with the setting of the core material or the permanent bonding of the covering sheets to the core, and in fact the use of the dispersion material enables a more secure bond to be attained between the core and the covering sheets. After the board is dried, the core set and the interposed layer of dispersion coalesced, the board may be advanced to further desired stages of treatment such as trimming, cutting of the continuous sheet into boards of desired length, et cetera.

In Fig. 2 I have illustrated, in section, the structure produced in accordance with my invention. As here shown the letter *a* indicates the inner core of plaster or stucco, the letters *b*, *b* the interposed layers of coalesced waterproofing material, and the letters *c*, *c* indicate the surfacing sheets affixed thereto.

In accordance with another embodiment of my invention I may apply the dispersion material on the exterior of the surfacing plies instead of between the surface or surfaces of the core and the inner face of the covering ply or plies. The advantages of my invention may be realized substantially fully as well 15 with this type of structure since the nature of the dispersion material as already described permits the complete evaporation of water from the core to take place through the porous surfacing ply or plies and the dispersion layer, the latter being transformed into a coalescent film only after substantially complete removal of the water contained therein and in the core. It is to be further noted in this connection that the utilization 20 of this embodiment of my invention does not present the difficulty that usually arises when applying waterproofing material such as asphalt in its normal condition, to the exterior of the surfacing ply or plies, namely, 25 that the surface thereof is too smooth for the proper retention of plaster thereon. I find that in this embodiment of my invention the waterproof film resulting from the complete removal of water from the core and the dispersion layer, possesses a sufficient degree of 30 "tooth" or "keying" property to enable plaster to stick thereto with adequate permanency.

In carrying out this embodiment of my invention the procedure may consist in forming the plaster board structure in the usual way and then, while the core material is still 40 green and unset, applying to the outer surfaces of the covering sheets, by means of a roll or doctor blade or by sprays, the dispersion material in a layer of desired thickness. Alternatively, if desired, the dispersion material may be applied to the external surface of the covering sheet or sheets prior 45 to the application of the green plaster material between the opposed inner surfaces of the sheets. The wet structure with its outermost layer of dispersion material may then be conducted through any convenient stage 50 for drying out the water and moisture of the inner core and the dispersion layer.

I have not shown in the drawings, the arrangement for carrying out this embodiment as it will be obvious to those skilled in the art 60 that it would be merely necessary in this instance, to transpose the dispersion applying device 12, 13 and 22, 23 to any convenient point following the application of the core material, instead of arranging the same, as 65 shown in Fig. 1, ahead of the delivery of the

core material between the surfacing sheets.

Another advantageous feature of this embodiment of my invention resides in the fact that the dispersion material may be made of a light colorable base such as resin, colorable asphalts or the like, so that the dispersion may be colored with any desired pigments or metallic powders to provide a decorative surface finish for the board structure which would enable the latter to be employed 70 as a wall board instead of as a base for subsequently applied plaster.

It will be appreciated by those skilled in the art that I should not regard it as a departure from my invention if the dispersion material were applied both interiorly and exteriorly of the surfacing sheet or sheets, as 75 obviously the advantages already pointed out would accrue to a structure made in this way.

Having thus described my invention, it will be evident to those skilled in the art that numerous changes and modifications may be made therein without departing from the spirit or scope of the invention as defined by the claims hereunto appended.

I claim as my invention:

1. The process of manufacturing plaster board, which comprises forming a core of plastic cementitious material and combining therewith a covering sheet of absorbent material having one of its surfaces coated with a layer of an aqueous dispersion of bituminous material.

2. The process of manufacturing plaster board, which comprises coating one surface of an absorbent sheet with an aqueous dispersion of bituminous material, forming a core of plastic cementitious material, and prior to substantial coalescence of said dispersion applying said sheet to the core with the coated surface thereof in contact with the core.

3. The process of manufacturing plaster board, which comprises coating the opposed surfaces of spaced absorbent plies of paper with a film composed of an aqueous dispersion of bituminous material, and prior to substantial coalescence of said dispersion interposing cementitious material between the coated plies to form a core therebetween.

4. The process of manufacturing plaster board, which comprises coating the opposed surfaces of spaced absorbent plies of paper with a film composed of a dispersion of bituminous material, said dispersion being of the type in which coalescence follows dehydration, and prior to substantial coalescence of said dispersion interposing cementitious material between the coated plies to form a core therebetween.

5. Plaster board, comprising an inner core of plaster or the like, a covering sheet of absorbent material adherent thereto, said covering sheet having associated with one of its surfaces a layer of bituminous material

coalesced from an aqueous dispersion of said bituminous material.

6. Plaster board, comprising an inner core of plaster or the like, a covering sheet
5 of absorbent material bonded thereto with an interposed layer of bituminous material coalesced from an aqueous dispersion of said bituminous material.

7. Plaster board, comprising an inner core
10 of plaster or the like and outer covering plies of absorbent material affixed thereto, there being a continuous film of bituminous material coalesced from an aqueous dispersion containing said bituminous material, interposed between said core and the opposed surfaces of the plies.

In testimony whereof I affix my signature.

HAROLD L. LEVIN.
